UNITED STATES PATENT OFFICE.

PETER G. GIROUD, OF NEW YORK, N. Y.

CLOCK.

No. 839,578.

Specification of Letters Patent.

Patented Dec. 25, 1906.

Application filed September 16, 1905. Serial No. 278,710.

To all whom it may concern:

Be it known that I, PETER G. GIROUD, a citizen of the United States, and a resident of the borough of Manhattan, in the city and State of New York, have invented a new and useful Improvement in Clocks, of which the following is a specification.

My invention relates to clocks, with the object in view of providing a clock in which the symbol indicating the hour shall be brought into view at the beginning of each succeeding hour, while the minutes and fractions of a minute may be read from a circular dial.

With these ends in view my invention consists in means for automatically jumping a dial-plate step by step at the beginning of each hour.

My invention further consists in a dial which shall expose the present hour-symbol only and on which the fractions of an hour may be read.

A practical embodiment of my invention is represented in the accompanying drawings, in which—

Figure 1 is a front view of so much of a clock as will suffice to disclose my present invention. Fig. 2 is a top plan view of the same. Fig. 3 is a vertical section in the plane of the line A A of Fig. 2. Fig. 4 is a vertical section in the plane of the line B B of Fig. 2. Fig. 5 is a similar view showing the position which the parts assume when the time is advanced toward a succeeding hour. Fig. 6 is a vertical section in the plane of the line C C of Fig. 2. Fig. 7 is a reverse view of the hour-dial plate represented in front in Fig. 3. Fig. 8 is a view in side elevation, and Fig. 9 is a partial vertical central section 40 from front to rear.

The face of the clock is denoted by 1. It is provided with a circular dial-plate 2 of any well-known or approved form, which dial-plate is herein shown as subdivided into minute-spaces from zero up to sixty and may be further subdivided into seconds in the usual manner, if so desired.

In the face 1, and preferably at the top and centrally over the minute-space zero, there is located an opening 3, through which the symbol indicating hour is intended to appear. In the present instance the symbol appearing through the opening 3 is shown as "7."

Behind the clock-face 1 there is located a series of symbols indicating the hours from

one to twelve, inclusive. These symbols are here shown as formed on a thin circular disk 4 and at such radial distances from the center of the disks as to bring the symbols indicating the hour consecutively before the opening 3 in the clock-face when the disk 4 is rotated.

The central arbor is denoted by 5. It carries on its end in front of the clock-face 1 a hand 6 for indicating the number of minutes on the dial 2. The arbor 5 is provided back of the face 1 with a sleeve 7, on which the hour-disk 4 is loosely mounted. For steady-ing the arbor I find it desirable to fix the rear end of the sleeve 7 in the downwardly-extending lip 8 of a bracket 9, made fast by a screw 10 to the frame-piece 11, the lip 8 being spaced from the face of the frame-piece 11 far enough to locate a drive-pinion 12, carried by the arbor 5 between the lip and the frame.

The clock-face 1 is fixed to the frame piece or plate 11 by posts 13 in any well-known or approved manner, and the said frame piece or plate 11, together with the sleeve 7, fixed on the lip 8, serves as an extended bearing for the arbor 5.

The drive-pinion 12 meshes with a spur-wheel 14, mounted on a stud 15, projecting from the face of the frame piece or plate 11, the said spur-wheel being provided with a series of pins 16, projecting from its face, in the present instance three, as clearly shown in Figs. 4 and 5. These pins located radi-ally equidistant from the axis of the wheel 14 act as cams for actuating a dog, as will be hereinafter explained.

The pins 16 on the wheel 14 serve to trip the hour-disk-actuating mechanism at inter-vals of one hour, as follows: From the back 95 of the hour-disk pins 17 project, twelve in number and spaced equal distances apart, one for each hour.

A longitudinally-reciprocating pawl or drive-bar is pivoted at one end at 19 to the upper end of a vibrating arm 20, the opposite end of the pawl or actuating-bar 18 being free to slide and move laterally in a bracket 21, fixed to the frame piece or plate 11. This pawl or actuating-bar 18 has a shoulder 105 22 at its extreme end to limit its movement in one direction and a shoulder 23 to limit its movement in the opposite direction. It also has a shoulder or nose 24 for engaging suc-cessively the pins 17.

To permit the bar 18 to lift away from the pins as it is withdrawn for the purpose of engaging a succeeding pin and at the same time to hold it positively in engagement with a pin at and near the limit of its advance movement, I provide the said bar with an incline 25 in proximity to the shoulder 23, which will widen the bar substantially to the limit of the slot in the bracket 21, through which it slides, while leaving the bar very much less in width than the width of the slot throughout the portion from the incline 25 to the shoulder 22 at its extreme end. This prevents the bar from escaping from the pin 17 as it nears the limit of its advance movement, and so insures the full throw of the disk 4 to present the hour plainly before the opening in the clock-face.

The vibrating arm 20 is mounted on a stud 26, projecting from the frame piece or plate 11 and is constantly pressed forward in a direction to move the hour-disk 4 by a spring 27.

There is also mounted to swing, together with the vibrating arm 20, a dog 28, having a hooked end 29, the outer face 30 of the said hook being in a position to engage the pins 16 on the spur-wheel 14.

The relation between the spur-wheel 14 and the dog 28 is such that as the spur-wheel 14 is rotated toward the left, as Figs. 4 and 5 are read, it will gradually slide along the face 30 of the dog and crowd the free end of the dog 28 back, thereby rocking the arm 20 on its support 26 and withdrawing the actuating-bar 18 into a position where it will engage a succeeding pin 17. It is shown approaching such a position in Fig. 5. This action of the dog 28 and lever 20 is against the tension of the spring 27, and the moment the pin 16 passes the end of the hook 29 the dog 28 and the lever 20, together with the bar 18, will be permitted to promptly spring forward under the tension of the spring 27, and the bar 18 will carry with it the hour-disk 4 one space to present a new hour-symbol before the opening 3 in the clock-face.

When the dog has sprung back into its position, as shown in Fig. 4, it will be possible to rotate the wheel 14 backwardly or in a direction to the right until the pin 16, previously engaged with the face of the dog, engages the bottom of the bight on the hook, at which point the backward turn of the wheel will be positively interrupted without derangement of any of the parts. This feature is of considerable importance, as it permits setting the clock backward past the hour position by turning the minute-hand without deranging the proper succession of hour-symbols and positively determines the limit of such backward movement.

The hour-disk 4 is held in its successive advanced positions by means of a retaining arm 31, pivoted on a stud 32, projecting

from the frame piece or plate 11 and pressed forwardly against two consecutive pins 17 by means of a spring 33. The blunt nose 34 of this retaining-pawl is normally seated between two consecutive pins, and the inclines 70 leading to the apex of the nose 34 are such as to permit the pins to slide along its face without any serious interruption when the hour-disk 4 is forced forward by the bar 18.

The central arbor 5 extends through the frame-piece 11 to a second frame-piece 35, the piece 35 being connected to the piece 11 by means of posts 36, as is common.

Between the pieces 11 and 35 the power-applying and escapement gear is located and may be of any well-known or approved construction. In the present instance I have shown a spring-actuated lever 37 pivoted to a stud 38, on which a ratchet-wheel 39 is loosely mounted, the lever 39 carrying a spring-actuated pawl 40 in position to engage the teeth on the periphery of the ratchet-wheel and to slide freely over the teeth when the lever 37 is swung in one direction and to cause the ratchet-wheel to rotate when the lever is swung in the opposite direction.

There is mounted to rotate with the ratchet-wheel 39 a spur-wheel 41, (see Fig. 6,) which intermeshes with a spur-wheel 42, fixed on the central arbor 5.

Communication from the wheel 42 to a suitable escapement mechanism (not shown) is made through a series of spur-wheels 43-44 45, the wheel 43 being provided with a pinion 46 in engagement with the wheel 42, the wheel 44 being provided with a pinion 47 in engagement with the wheel 43, and the wheel 45 being provided with a pinion 48 in engagement with the wheel 44.

The lever 37 may be rocked either by electricity or by a pendulum or other power, the particular means of rocking this power-lever forming no part of my present invention.

In operation, assuming that the wheel 42, and hence the arbor 5, to be driven at minute intervals by the action of the lever 37, the minute-hand 6 will be moved step by step around the dial 2 until sixty minutes have been recorded, at which moment a pin 16 on the wheel 14 will slip past the nose of the dog 28, and the hour-disk 40 will be advanced to bring the symbol indicating the next succeeding hour before the opening 3 in the clock-face.

The device is a simple one. It brings the hour plainly to the front without confusion, while the number of minutes between consecutive hours may be read without the confusion commonly incident to a multiplicity of pointers on the clock-face.

In employing the word "clock" I wish to be understood as including any timepiece to which my invention may be applicable.

It is evident that changes might be resorted to in the form and arrangement of the sev-

eral parts without departing from the spirit and scope of my invention. Hence I do not wish to limit myself strictly to the structure herein shown and described; but

5. What I claim is—

1. In a clock, means for imparting a step-by-step movement to a disk, comprising a spring-actuated vibrating lever, means for operating the lever, a fixed guide and a sliding bar pivoted to the lever and extending through the guide, the said bar being provided with an abutment for engaging the part to be operated, with an incline for holding the bar to its work and with shoulders for limiting the movement of the bar.
2. In a clock, the central arbor provided with a pinion, a wheel in gear with the pinion and provided with laterally-projecting pins at intervals on its face, a rock-shaft, a hook-lever fixed on the rock-shaft with its hooked

end in position to be engaged by the said pins to rock the shaft, a second lever fixed to the rock-shaft, a disk on the central arbor and provided with pins projecting laterally therefrom at intervals along its back, a fixed guide and a longitudinally-sliding bar held in the guide and pivotally secured to the said second lever, the said sliding bar being provided with an abutment for engaging a pin on the disk, an incline for engaging the guide and with shoulders to limit its sliding movements.

In testimony that I claim the foregoing as my invention I have signed my name, in presence of two witnesses, this 14th day of September, 1905.

PETER G. GIROUD.
